(57) **CLAIM**

The ornamental design for a circular saw portion, as shown and described.

DESCRIPTION

FIG. 1 is a right side perspective view from the front of a circular saw portion showing my new design;

FIG. 2 is a right side elevational view of the circular saw portion;

FIG. 3 is a left side elevational view of the circular saw portion;

FIG. 4 is a front elevational view of the circular saw portion;

FIG. 5 is a rear elevational view of the circular saw portion;

FIG. 6 is a top plan view of the circular saw portion; and,

FIG. 7 is a bottom plan view of the circular saw portion.

The broken line showing is for illustrative purposes only and forms no part of the claimed design.
